UNITED STATES PATENT OFFICE.

ANNA J. MOSS AND CLARA L. MOSS, OF COLLINGSWOOD, NEW JERSEY.

DESIGN FOR A POISON-BOTTLE.

46,407.

Specification for Design.

Patented Sept. 15, 1914.

Application filed June 18, 1914. Serial No. 845,942. Term of patent 14 years.

To all whom it may concern:

Be it known that we, ANNA J. Moss and CLARA L. Moss, citizens of the United States, residing at Collingswood, in the county of Camden and State of New Jersey, have invented a new and original and ornamental Design for Poison-Bottles, of which the following is a specification, reference being had to the accompanying drawing, forming a part thereof.

Figure 1, is a front elevation of a poison

bottle showing our new design, and Fig. 2, a side elevation thereof.

We claim—

The ornamental design for a poison bottle as shown.

ANNA J. MOSS.
CLARA L. MOSS.
